HYDRAULIC MOTOR AND PUMP

Hans Thoma, Karlsruhe, Germany

Application March 17, 1933, Serial No. 661,358
In Germany March 30, 1932

4 Claims. (Cl. 103—162)

This invention relates to hydraulic motors and pumps and has particular reference to such devices provided with oscillatable cylinders arranged generally parallel. In such devices it is customary, to accommodate the oscillatable cylinders in a bell-shaped element, the rim of the bell serving for carrying the journals through which the oil feed is mostly effected. The closed, bell-shaped construction has been preferably employed in the belief that this alone imparts the necessary rigidity for preventing vibrations as produced by the varying piston forces.

The invention is based on the knowledge that this manner of imparting rigidity is neither necessary nor practical. It is correct, to make the journals and their bearings rigid. However, for this purpose it is sufficient to correspondingly reinforce the connections arranged directly between the journals and the valve face, which connections are mostly made hollow for feeding the oil. These parts alone ensure an absorption of the principal piston forces almost without sagging, whereas the usual lateral walls of the bell, owing to their curved shape impart only an apparent but in reality immaterial rigidity.

According to the invention, an open oscillatably mounted frame or U-shaped yoke is therefore employed, which presents the great advantage that the oil running off the valve face in service is easily visible, so that it is possible to ascertain whether, for example, too much oil flows through the control gear.

An embodiment of the invention is illustrated by way of example in the accompanying drawing in which:

Fig. 1 shows in side elevation a hydraulic motor or pump illustrating the present invention.

Fig. 2 is a partial longitudinal section of Fig. 1.

Fig. 3 is a partial section of the device showing the valve face.

A shaft W is guided in suitable radial and axial bearings and carries the driving flange T. Connecting rods P provided with the usual balls are hinged to this driving flange T. The connecting rods P serve for driving the pistons not shown in the drawing located in a rotary cylinder block Z. The cylinder block Z carries a valve surface S, which cooperates with a corresponding stationary valve surface to effect the necessary valving of the fluid in the cylinders.

This valve face is, according to the invention, not arranged in the interior of a closed bell, but in a frame or yoke R which is so formed as to present to view the junction of the cylinder block with the valve face. The important feature is,

the arrangement of a frame or yoke R which is for the greater part open and which presents a clear view of the important parts of the cooperating cylinder and valve surface especially the oil flow from the valve face. The parts of the frame R may at the same time be made hollow for the oil feed and discharge. The parts of the frame R may be cast in one-piece with the valve body or bolted thereon. In the case of large size constructions and high oil pressures which act on the pivot pins Z, an undesirable resilient yielding of the frame R might however occur. In order to prevent this, staybolts B or other supporting elements pressed or cast in a suitable manner between the arms may be employed which however should be so constructed as to leave between the valve face S and the supporting elements an ample window aperture through which the working of the control gear or the quantity of oil running off can be observed.

The essential feature is the arrangement of an open frame element or yoke for hydraulic motors or pumps with oscillatably mounted cylinders in such a manner that the operation of the valve surfaces and the quantity of oil flowing off therefrom can be observed. The staybolts B may at the same time serve as connecting means for a driving member for the adjusting mechanism, for example for a screw spindle Sch which is hingedly connected on one side of the frame. On the other staybolt for example intermediate springs, indicating devices or the like can act. The screw spindle and the other parts can be keyed as required on the upwardly or downwardly extended bolt B, or, if a cast or otherwise inserted constructional element is employed instead of the bolt B, an eye, a separate bolt or the like may be provided thereon for this purpose.

The oscillatable frame or yoke may have a cover to avoid throwing about of lubricating oil.

Having thus described an illustrative embodiment of the invention what I claim is:

1. In a hydraulic motor or pump, the combination comprising a rotatable shaft, a bearing for said shaft, a generally U-shaped yoke pivotally connected to a support, the base of said yoke being provided with a bearing surface having valve ports therein and with spaced generally parallel arms attached to said base on opposite sides thereof and extending from said base toward said support, each of which arms is formed with a passageway communicating with one of said valve ports, a rotatable cylinder member having cooperating ports therein connected for rotation with said shaft, bearing against said surface with its

ports communicating alternately with the ports in said bearing surface, said bearing surface being located between the arms, and the space between said arms adjacent said bearing surface being left open to provide access to said bearing surface from the side and to permit observation of the operation of said rotatable cylinder member in relation to said bearing surface.

5 2. In a hydraulic motor or pump, the combination comprising a rotatable shaft, a bearing for said shaft, a cylinder support member pivotally connected to a support, said pivoted member being provided with a base formed with a surface having valve ports therein and with spaced generally parallel arms attached to said base on opposite sides thereof and extending from said base toward said support, said cylinder support member being formed with passageways communicating with said valve ports, a rotatable cylinder member having cooperating ports therein connected for rotation with said shaft, bearing against said surface with its ports communicating alternately with the ports in said bearing surface, said bearing surface being located between the arms and the space between said arms and adjacent said bearing surface being left open to provide access to said bearing surface from the side and to permit observation of the operation of said rotatable cylinder member in relation to said bearing surface.

10 3. In a hydraulic motor or pump, the combination comprising a rotatable shaft, a bearing for said shaft, a cylinder support member pivotally connected to a support, said pivoted member being provided with a base formed with a surface having valve ports therein and with spaced generally parallel arms attached to said base on opposite sides thereof and extending from said base

toward said support, said cylinder support member being formed with passageways communicating with said valve ports, a rotatable cylinder member having cooperating ports therein connected for rotation with said shaft located adjacent said valve surface with its ports communicating alternately with the ports in said valve surface, said valve surface being located between the arms and the space between said arms and adjacent said valve surface being left open to provide access to said surface from the side and to permit observation of the operation of said rotatable cylinder member in relation to said valve surface.

15 4. In a hydraulic motor or pump, the combination comprising a rotatable shaft, a bearing for said shaft, a cylinder support member pivotally connected to a support, said pivoted member being provided with a base formed with a surface having valve ports therein and with spaced generally parallel arms attached to said base on opposite sides thereof and extending from said base toward said support, said cylinder support being formed with passageways communicating with said valve ports, a rotatable cylinder member having cooperating ports therein connected for rotation with said shaft located adjacent said valve surface with its ports communicating alternately with the ports in said valve surface, said valve surface being located between the arms and the space between said arms and adjacent said valve surface being left open to provide access to said surface from the side and to permit observation of the operation of said rotatable cylinder member in relation to said valve surface, said spaced arms being provided with transverse connecting means adjacent their pivoted ends.

HANS THOMA.
